OTHER PUBLICATIONS

Photograph, 8611P Device, Front View, The 8611P device of Standard Motor Products, Inc., is a unitary camshaft seal and PCV valve bolted to a valve cover in an engine. The 8611P device has two apertures to receive fasteners to bolt the device to the valve cover. The device forms a seal with the valve cover when bolted in place.

(57) **CLAIM**

The ornamental design for a combined positive crankcase ventilation valve and dynamic camshaft seal, as shown and described.

DESCRIPTION

FIG. 1 is a perspective front view of a combined positive crankcase ventilation valve and dynamic camshaft seal showing my new design;

FIG. 2 is a front elevation view;

FIG. 3 is a rear elevation view;

FIG. 4 is a left side elevation view;

FIG. 5 is a right side elevation view;

FIG. 6 is a top plan view;

FIG. 7 is a bottom plan view; and,

FIG. 8 is a rear perspective view.

Structure shown in broken line forming no part of the claimed design.
